UNITED STATES PATENT OFFICE.

JOSEPH O. NEEL, OF KINGSLAND, ARKANSAS.

DESIGN FOR A BASKET.

SPECIFICATION forming part of Design No. 27,574, dated August 24, 1897.

Application filed April 6, 1897. Serial No. 631,031. Term of patent 7 years.

To all whom it may concern:

Be it known that I, JOSEPH O. NEEL, a citizen of the United States, residing at Kingsland, in the county of Cleveland and State of Arkansas, have invented and produced a certain new and original design for Cotton-Handling Baskets; and I do declare the following to be a full, clear, and exact description of the invention, such as will enable others skilled in the art to which it appertains to make and use the same.

My invention relates to a design for a basket.

My design relates particularly to the basket as illustrated in the accompanying drawings, in which—

Figure 1 is a view in perspective of a basket, illustrating my design; and Fig. 2 is a detail view of the same.

The leading features of my design appear in the following description.

1 represents the circular reticulated bottom, around the outer edge of which is arranged a brace-ring 2.

3 represents the cylindrical body, the reticulated walls of which bulge slightly from the bottom 1 to the angular corrugated edge 4.

A circular brace-ring 5 extends around the outside of the upper portion of the basket a short distance below the corrugated edge. 30

Semicylindrical handles 6 appear on opposite sides of the brace-ring 5, and their upper edges extend above the upper edge of the mouth of the basket.

The basket is made up of wire strands, 35 which are fluted or waved, and the body of the basket bulges beyond its top and bottom edges, as shown.

Having thus fully described my invention, what I claim as new, and desire to secure by 40 Letters Patent of the United States, is—

The design for a basket made of fluted or corrugated strands, having a round flat bottom, a flaring mouth terminating in a corrugated edge and having convex sides, bulging 45 laterally beyond said flaring mouth, substantially as herein shown and described.

In testimony whereof I hereunto affix my signature in presence of two witnesses.

JOSEPH O. NEEL.
